Primary Examiner — Carol P Rademaker(74) *Attorney, Agent, or Firm* — Muncy, Geissler, Olds & Lowe, PLLC(57) **CLAIM**

The ornamental design for a bottle, as shown and described.

DESCRIPTION

FIG. 1 is a front elevational view of a bottle showing my new design;
FIG. 2 is a rear elevational view of the bottle;

FIG. 3 is a left side view of the bottle;

FIG. 4 is a right side view of the bottle; and,

FIG. 5 is a top plan view of the bottle.

The dash-dash-dash type broken lines shown in the drawing views are included for the purpose of illustrating environmental structure and form no part of the claimed design.

The dash-dot-dash-dot type broken lines shown in the drawing views define the boundaries of the claimed design.
